UNITED STATES PATENT OFFICE.

SAMUEL S. SENCENBAUGH, OF AURORA, ILLINOIS, ASSIGNOR OF ONE-HALF
TO GEORGE V. HARVEY AND CHARLES O. BORING, BOTH OF CHICAGO,
ILLINOIS.

TAG-FASTENER.

SPECIFICATION forming part of Letters Patent No. 313,539, dated March 10, 1885.

Application filed June 16, 1884. (No model.)

To all whom it may concern:

Be it known that I, SAMUEL S. SENCENBAUGH, a citizen of the United States, residing at Aurora, in the county of Kane and State of Illinois, have invented certain new and useful Improvements in Tag-Fasteners, my present invention being an improvement upon the tag-fastener described in Letters Patent of the United States No. 298,629, granted to me May 10, 1884, and being especially adapted for attaching tags or labels to fibrous goods, of which the following is a specification.

In the drawings, Figure 1 represents my tag-fastener partially completed—that is, before the ends of the shanks or arms A and B shall have been turned into hooks, as shown in dotted lines; and Fig. 2 represents one form of a tag-fastener in which my invention appears.

I construct this tag-fastener of metal or wire, and having duplicated it upon itself so as to form the loop C for the tag or label, which loop or eye may be of any desired form or shape, and may be constructed in any plane with reference to the plane of the arms or shanks A B, I elliptically and inwardly bend back the shanks or arms so as to form hooks, each of the points of which hooks impinge against or upon some portion of the other shank or arm. The shanks or arms are preferably of different lengths, and I have so illustrated them in the drawings. A less convenient form of my invention is to make the shanks or arms shown in the drawings of equal length, the hooks in either case being adapted to seize the goods or article to be labeled by inserting the same between the said shanks or arms and by turning or revolving the fastener one-quarter round, more or less, and then withdrawing the same a little, whereupon the hooks will engage in the goods or package to be labeled. I prefer that the longer shank shall be so bent as that its point shall rest, not against but upon one side of the oval bend in the other shank, so as that they shall be maintained in different planes to facilitate the introduction of the goods between them; but this is not essential, for if they are so con-

structed as that they may rest in the same plane it is an easy matter to so manipulate them in applying them as that they shall be separated and the goods inserted as aforesaid. I also prefer that the hook on the longer of the said shanks or arms shall be so bent as that its point shall rest against the side of the oval bend in the other arm, and the hook of the shorter arm shall be so bent and twisted as to rest against the inner side of the longer shank or arm, in which shape my said fastener becomes a safety-fastener in which the points are protected against accidentally engaging, and in which construction this tag-fastener is more convenient for packing and shipping.

It is not essential to my invention that the shanks or arms should be of different lengths; but it is very desirable, if of the same length, the shanks should be turned elliptically and inwardly upon each other, so that the point of each hook will rest against the front or rear side of the other shank.

Having thus described my invention, what I claim, and desire to secure by Letters Patent, is—

1. An improved tag-fastener consisting of a wire bent to form two parallel shanks or arms which terminate in hooks, each bent inwardly, the points of the said hooks resting, respectively, against the body portion of the other shank or arm, all substantially as shown and described.

2. An improved tag-fastener consisting of a wire bent to form two parallel shanks or arms of unequal length, each terminating in hooks, each bent inwardly, the point of the hook of the longer arm resting against the body portion of the hook of the shorter arm, all substantially as shown and described.

In witness whereof I have hereunto set my hand this 14th day of June, A. D. 1884.

SAMUEL S. SENCENBAUGH.
